REFRIGERATOR CONTROL SYSTEM

Joseph N. Roth, Belding, Mich., assignor, by
mesne assignments, to Gibson Refrigerator
Company, Greenville, Mich., a corporation of
Michigan

Application June 27, 1941, Serial No. 400,089

9 Claims. (Cl. 62—5)

This invention relates to a refrigerator control system, and more particularly to means for controlling the delivery of refrigerant from a high pressure portion to a low pressure portion of a refrigeration system.

One feature of this invention is that it provides improved means for controlling delivery of liquefied refrigerant from the condenser to the evaporator of a continuous absorption refrigeration system; another feature of this invention is that it provides for complete stoppage of refrigerant flow to the evaporator at desired periods; another feature of this invention is that it obviates the need of a flow controlled or other type of expansion valve assuming partially open positions and liable to wire drawing and similar difficulties; a further feature of this invention is that it is particularly adapted for use in a continuous absorption refrigeration system of the type using a transfer chamber to return liquor from the absorber to the still, and where transfer action is controlled by balancing still pressure against another force; other features and advantages of this invention will be apparent from the following specification and the drawings, in which:

Figure 1 is a schematic or diagrammatic showing of a system employing this invention as embodied in a domestic continuous absorption refrigerator; Figure 2 is a detail view, principally in vertical section, of the capillary tube portion of the system; Figure 3 is a top plan view of the valve unit; Figure 4 is a detail view, principally in cross section, of the valve unit, along the line 4—4 of Figure 3; Figure 5 is fragmentary transverse sectional view along the line 5—5 of Figure 3; Figure 6 is a chart of still pressure in apparatus not incorporating my invention; Figure 7 is a chart showing evaporator temperature in the same apparatus; Figure 8 is a chart showing still pressure in the same apparatus where my invention is used; and Figure 9 is a chart showing evaporator temperature in the apparatus of Figure 8.

In the particular embodiment of my invention described herewith, the system in general comprises a still adapted to have a mixture of refrigerant and absorbent, as ammonia and water, boiled therein by the application of heat; a condenser connected by a vapor conduit to the still to liquefy the refrigerant vapor delivered thereby; an evaporator or cooling unit in which the liquefied refrigerant is permitted to vaporize, the evaporator having restricted connection with the condenser; an absorber in which the gas from

the evaporator is reabsorbed in liquid; and means for effecting flow of weak liquor from the bottom of the still to the absorber and flow of rich liquor from the bottom of the absorber to the still. This latter means includes a transfer chamber intermediate the absorber and the still and a valve arrangement whereby the chamber is selectively connected to the absorber or to the still.

Referring more particularly to a specific system schematically or diagrammatically illustrated in Figure 1, the still 10 is adapted to contain a mixture of water and ammonia. A flue 11 is provided within the still and heat delivered thereto by the combustion of gas or some other fuel delivered by the burner 12. An analyzer tower 13, in the form of a long cylindrical tubing enclosing the flue 11, rises from the upper part of the still, which is a vertical cylindrical vessel. Both the analyzer tower and the still are provided with baffle plates, as 14 and 15, these plates serving to stratify the liquid in the still and to improve the efficiency of the apparatus.

Rich ammonia vapors boiled off the liquor in the still pass upwardly through the analyzer tower 13 and then through the pipe connection 16 to the rectifier 17, a finned inclined tube at the top of the system. From there the ammonia vapors, any entrained water vapor having been removed by the rectifier, pass down through the connection 18 to a condenser 19 at the lower end of the apparatus. This condenser comprises one or more loops of piping, finned to increase the heat radiation. The ammonia vapor is here condensed into liquid ammonia, and then elevated by the vapor pressure behind it through the connection 20, a valve unit here indicated in general as 21, and the connection 22 to the receiver 23.

The amount of ammonia boiled off and liquefied is a function of the concentration of the liquor in the still and of the amount of heat supplied to it, so that if the concentration of liquor is kept relatively constant the rate of delivery of liquid ammonia to the receiver 21 will be practically a direct function of the amount of heat supplied to the still. The amount of fuel delivered to the burner 12, and thus the amount of heat supplied and the rate of delivery of liquid ammonia to the receiver, can be regulated in any desired manner, as by a valve (not here shown) actuated in conventional manner by a thermostat in the cooling chamber of the refrigerator.

Liquid ammonia passes from the receiver 23 to the dry evaporator 24, preferably comprising

several loops or coils of tubing, through the restriction interposed by a capillary tube which will hereafter be described in more detail. The control arrangement is such that, as more liquid ammonia is delivered to the receiver, flow from the receiver to the evaporator is increased to maintain the level of the liquid in the receiver within certain desired limits.

Absorbing apparatus is provided in the form of an upper chamber or vessel 25 having an outlet pipe 26 at the bottom thereof leading to a liquid jacket 27 around a transfer chamber 28, and a flow path from the jacket down through the pipe 29, the finned absorber cooling coil 30, and the upwardly extending pipe or leg 31, this leg terminating in the absorber at a point slightly above the level of absorption liquid therein. This arrangement provides a cooling loop, liquid from the bottom of the absorber vessel 25 passing down through the jacket 27 and the pipe 29 to the cooling coil 30, then returning through the pipe 31, the circulation being maintained when the refrigeration system is in operation by vapor admitted to this pipe 31.

The expanded ammonia vapor from the evaporator 24 passes down through the pipe 32 and loops around at the bottom to admit the vapor to the rising leg 31 of the absorber cooling loop, this providing the liquid lift necessary to insure circulation. Inasmuch as the liquid in this rising leg is at all times the weakest liquor in the absorber, and cooled by its passage through the absorber cooling coil 30, all absorption normally takes place in the pipe 31, the enriched liquor flowing out of the top of this pipe. The desired level of liquid in the absorber vessel 25 is maintained by a valve 33 controlling delivery of weak liquor from the still, this valve being actuated by a float 34. A pipe 35 leads from the lower end of the still (where the liquor is weakest because of the stratification effected by the baffles 15) through a heat exchanger 36 and then on up to open into the absorber. The pressure in the still or generator 10 at all times tends to drive liquid up this pipe 35, and its admission to the absorber is controlled by the float valve 33, so that any removal of liquor from the absorber causes an immediate replacement of its contents.

The means for returning rich liquor from the absorber to the still, necessary because this liquor must be returned despite the fact that the evaporator and absorber operate at low pressure and the still operates at high pressure, comprises as its principal parts the transfer chamber 28 and the valve unit 21. A flow connection from the absorber to the transfer chamber is provided from the tube 31, out through the short open-ended cross tube 37 connecting therewith, then through the jacket 38, the pipe 39, and the check valve 40 into the transfer chamber. When the movable valve means in the valve unit 21 is set in a certain position the transfer chamber is connected to the still 10 by connecting the pipe 41 leading from the high pressure vapor line 18 to the pipe 42 opening into the top of the transfer chamber; and by connecting the pipe 43 leading out of the bottom of the transfer chamber to the pipe 44. This latter pipe passes through the heat exchanger 36, through a jacket 45 around a thermostat bulb 46, and through the pipe 47 to open into the analyzer tower 13. In this setting of the valve means high pressure vapor admitted to the top of the transfer chamber equalizes its pressure with that in the still, so that liquid in the transfer chamber drains down through the path just 75

described, starting with the pipe 44, into the still.

When the movable valve means is moved to its other setting the transfer chamber is disconnected from the still by blocking the connection between the pipes 41 and 42 and between the pipes 43 and 44. A very fine weak liquor bleeder orifice or passageway, here indicated as 48, delivers weak liquor under still pressure from the tube 35 to the top of the transfer chamber, and as soon as this chamber is disconnected from the still this weak liquor begins to absorb the high pressure vapor in the transfer chamber. This absorption progresses very rapidly to the point where the transfer chamber pressure drops below the pressure in the absorber, whereupon the check valve 40 opens and the transfer chamber refills with rich liquor from the absorber. As this takes place the level of the liquid in the absorber is maintained by opening of the valve 33 by the float 34, as mentioned heretofore. As soon as the transfer chamber fills up solidly with liquid the weak liquor bleeder 48 raises its pressure to that in the still, so that only for the brief period necessary to refill the transfer chamber is there a complete pressure differential across the valve means in the valve unit 21.

Actuation of the valve means in the valve unit 21 is accomplished by the thermostat bulb 46 previously mentioned, located in the still 10 below the normal level of liquid therein, but surrounded by the jacket 45. This thermostat bulb is connected by a liquid actuating leg 49 to a chamber in the bottom of the valve unit 21. This chamber is divided into two parts by a sylphon bellows or similar arrangement, and still pressure is present in the upper part of the chamber, above the bellows, at all times by reason of the fact that the pipe 44 opens into this chamber; and this pressure is balanced against another force, in this case the force of liquid delivered by the actuating leg 49 as a result of pressure generated in the thermostat bulb 46. As may be best seen in Figures 3 to 5, the valve unit includes snap action mechanism here identified in general as 50, so that when the still pressure exceeds the thermostat liquid pressure force the movable member 51 is in lower position, as shown in the drawings; and when the liquid thermostat force sufficiently exceeds still pressure the member 51 is moved to upper position. The thermostat bulb 46 is preferably filled with a predetermined concentration of the refrigerant and absorbent used, as water and ammonia, so that the pressure in the thermostat rises rapidly whenever the concentration of liquor in the still drops below that in the bulb.

When the transfer chamber is connected to the still relatively cool liquid flowing back to the still, by passing through the jacket 45 around the bulb 46, cools the bulb fairly rapidly and causes the thermostat bulb pressure to drop below still pressure sooner than would otherwise be the case.

Referring now more particularly to Figures 4 and 5, it will be seen that in the normal position of the valve member 52, as shown, connection between the pipes 41 and 42 is blocked, as is also connection between the pipe 43 and the chamber within the valve unit; while connection between the pipes 20 and 22 is completed to permit flow of refrigerant from the condenser 19 to the receiver 23. When thermostat pressure sufficiently exceeds still pressure to overcome the resistance of the snap action mechanism the valve member 52 is moved to upper position, in which position the annular groove 53 lines up exactly with the passageways 54 and 55 completing connection be-

tween the pipes 41 and 42 (see Figure 4); the orifice 56 is covered to block connection between the pipes 20 and 22 (see Figure 5); and the orifice 57 is uncovered by the bottom of the valve member 52 to permit liquid from the pipe 43 to flow into the upper part of the chamber within the valve unit or housing.

Turning now more particularly to Figure 2, it will be seen that liquid refrigerant in the receiver 23 passes through the strainer or filter unit 58 into the interior chamber 59. Communication between this chamber and the evaporator 24 is provided by the capillary tube 60, the major part of this capillary tube being coiled up within the receiver 23. Because of this coiling arrangement variations in liquid level within the receiver 23 cause variations in heat exchange with the contents of the capillary tube 60, which in turn causes variation in the rate of movement of refrigerant therethrough. The arrangement is such that the rate of movement of refrigerant through the capillary 60 is at least partially a function of the rate of delivery of liquid refrigerant to the receiver 23. If the coiled portion of the capillary is completely submerged the refrigerant will pass through the capillary tube substantially entirely in liquid state, at a considerable rate of flow; whereas if the level of liquid in the receiver drops there will be a heat exchange between the exposed part of the capillary and the vapor at condenser temperature and pressure in the upper part of the receiver 23, causing vaporization of some of the liquid in the capillary tube and consequent retarding of the flow of refrigerant therethrough. This particular feature of my refrigerant flow control arrangement forms the subject matter of my co-pending application Serial No. 361,629, filed October 17, 1940, and it will not, therefore, be further described.

While the continuous absorption refrigeration system shown schematically in Figure 1 and described in general hereabove contains a number of inventions and improvements, this present application is directed to means for controlling delivery of refrigerant from the condenser in the high pressure side of the system to the evaporator in the low pressure side, where a valve is used in series with a capillary tube. Other improvements in the system are the subject matter of my earlier filed joint and several co-pending applications, more particularly applications Serial No. 296,995, filed September 28, 1939, Serial No. 298,110, filed October 5, 1939, Serial No. 326,292, filed March 27, 1940, Serial No. 314,704, filed January 19, 1940, Serial No. 319,541, filed February 17, 1940, Serial No. 352,328, filed August 12, 1940, Serial No. 388,155, filed April 11, 1941, and Serial No. 394,031, filed May 17, 1941.

Control of transfer action by balancing still pressure against the force generated by a thermostat exposed to the temperature of liquor in the still is very desirable in a refrigeration system of the type here disclosed, since it provides automatic compensation for a number of variables which would otherwise upset the system, maintaining proper quantities and concentrations of liquor in various parts of the system despite varying room temperatures, food compartment loads, and the like, as was brought out more fully in my above-mentioned application Serial No. 296,995. In order to keep the refrigerator from shutting down upon a transfer operation the valves must be reversed before the transfer chamber has completely emptied itself of liquid, preferably when there is still one-quarter or one-

third of the contents remaining in the chamber. When float-actuated expansion valves are used there is no difficulty in this regard, but it is highly desirable to avoid another set of moving parts, and particularly an expansion valve which frequently opens only partially and causes wire drawing and undesired erosion of the valve seat. For this reason it is preferable to use a capillary tube to provide the desired restriction to flow from the high pressure condenser to the low pressure evaporator.

The use of a capillary as the restrictor, however, presented an unexpected and unobvious difficulty in that it provided a continuous bleeding off of pressure from the high pressure side of the system and, when in a particular combination of circumstances, caused the still pressure to drop faster than the thermostat bulb pressure upon transfer action, so that the valves failed to stop transfer action before the chamber emptied itself, occasionally causing the system to shut down and fail to function.

Referring now more particularly to the charts of Figures 6 and 7, it will be noted that the still or generator pressure chart has had various points identified by a T to indicate when transfer took place in a domestic absorption refrigerator machine embodying all of the previously described structure except valve means in series with the capillary. On the initial declining slope of the curve it will be understood that the evaporator temperature was low enough that the thermostat in the food chamber had the burner beneath the still turned down to its lowest, a mere pilot flame. At about the bottom of the curve, after about fifteen minutes of run, it will be noted that the evaporator temperature has risen to about seven degrees, and this is sufficient to cause the burner to be turned up to a light flame. The evaporator temperature still rising, the burner shortly thereafter is turned up to medium and then to full flame, so that the still pressure shown on the first chart begins to rise rapidly. Under such circumstances, despite the dumping of relatively cool liquor into the still upon the transfer action, the still pressure rises (even though not quite so sharply) upon each of the succeeding transfer operations at about 28 minutes and 38 minutes. By this time, however, the evaporator temperature has begun to drop and the burner is turned down through medium to pilot, so that from forty-five minutes on the still pressure drops sharply. Under these conditions it will be noted that when a transfer action is initiated at about fifty-seven minutes the still pressure is dropping rapidly, and it is under conditions such as these that the still pressure sometimes outruns the drop in thermostat bulb pressure; and if this occurs the valves fail to reverse their positions and the system may shut down.

While I have now discovered this to be the reason for occasional failure of the system, it was not obvious and required a long period of research and checking before I did discover the difficulty and solve the problem of overcoming it, by putting in series with the capillary tube a valve which is shut while the transfer chamber is emptying to the still, being open at other times.

Turning now to Figures 8 and 9, illustrating generator pressures and evaporator temperatures in apparatus wherein the connection from the condenser to the capillary tube is through the valve unit, as described heretofore, it will be seen that there is always a rise in generator pressure, or at least a maintenance of such pressure con-

stant, at the time of transfer action. Calling attention to the transfer actions taking place on declining portions of the still pressure curves, at fourteen minutes, twenty-one minutes, fifty minutes and sixty minutes, it will be noticed that there is a rise in still pressure incident to each transfer operation. Moreover, although it does not show on these charts, the arrangement tends to prevent wide swings in the burner from pilot to full, there being more periods of light and medium operation tending to maintain a smooth and more stable action of the system.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. Apparatus of the character described for controlling delivery of refrigerant from a high pressure portion to a low pressure portion of a continuous absorption refrigeration system incorporating means for periodically returning liquor from the low pressure portion to the high pressure portion and wherein the high pressure portion includes a still, including: a capillary tube element designed to receive the entire pressure differential in the system; a valve element including a valve member adapted to be moved to open or closed position and so constructed as to always remain either in fully open or fully closed position, said elements being parts of a flow path connecting the high and low pressure portions and all of the refrigerant flowing through said path passing through both of said elements; and means for moving said valve member, said means being responsive to a condition in the still.

2. Apparatus of the character described for controlling delivery of refrigerant from a high pressure portion to a low pressure portion of a continuous absorption refrigeration system incorporating means for periodically returning liquor from the low pressure portion to the high pressure portion, including: a capillary tube element; a valve element including a valve member adapted to be moved to open or closed position, said elements being parts of a flow path connecting the high and low pressure portions and all of the refrigerant flowing through said path passing through both of said elements; and means for moving said valve member, said means being responsive to the concentration of refrigerant in a part of the high pressure portion.

3. A continuous absorption refrigeration system of the character described, including: a still; a condenser, the still and condenser being adapted to operate at high pressure; an evaporator; an absorber, the evaporator and absorber being adapted to operate at low pressure; transfer means for periodically returning liquor from the absorber to the still; means connecting the condenser and evaporator, said means including a capillary tube and a valve; and means responsive to a condition in the system for opening and closing said valve, the operation of the valve being correlated with that of the transfer means.

4. A continuous absorption refrigeration system of the character described, including: a still;

a condenser, the still and condenser being adapted to operate at high pressure; an evaporator; an absorber, the evaporator and absorber being adapted to operate at low pressure; transfer means for periodically returning liquor from the absorber to the still; means connecting the condenser and evaporator, said means including a capillary tube and a valve; and actuating means for effecting operation of the transfer means and the valve, the arrangement being such that the valve is closed when the transfer means is returning liquor to the still.

5. Apparatus of the character claimed in claim 3, wherein the actuating means is responsive to still pressure and another condition in the system.

6. A continuous absorption refrigeration system of the character described, including: a still; a condenser, the still and condenser being adapted to operate at high pressure; an evaporator; an absorber, the evaporator and absorber being adapted to operate at low pressure; transfer means for periodically returning liquor from the absorber to the still; means connecting the condenser and evaporator, said means including a capillary tube and a valve; and actuating means responsive to the difference between still pressure and another force, the actuating means effecting operation of the transfer means and the valve and the arrangement being such that liquor is moved from the transfer means to the still and said valve is closed when said force exceeds still pressure and movement of liquor to the still is terminated and said valve is opened when still pressure exceeds said force.

7. A continuous absorption refrigeration system of the character described, including: a still; a condenser, the still and condenser being adapted to operate at high pressure; an evaporator; an absorber, the evaporator and absorber being adapted to operate at low pressure; a transfer chamber; a connection between the condenser and the evaporator including a capillary tube; a valve unit having movable valve means adapted in one position to connect the transfer chamber to the absorber and complete the connection between the condenser and the evaporator, and in another position to connect the transfer chamber to the still and block the connection between the condenser and the evaporator; and actuating means for moving the valve means, said actuating means being responsive to the difference between still pressure and another force.

8. Apparatus of the character claimed in claim 7, wherein the arrangement is such that the valve means is in the last mentioned position when still pressure exceeds the other force.

9. Apparatus of the character described for controlling delivery of refrigerant from a high pressure portion to a low pressure portion of an absorption refrigeration system and wherein the high pressure portion includes a still, including: a capillary tube element; a valve element including a valve member adapted to be moved to open or closed position, said elements being parts of a flow path connecting the high and low pressure portions and all of the refrigerant flowing through said path passing through both of said elements; and means for moving said valve member, said means being responsive to a condition in the still.
